UNITED STATES PATENT OFFICE.

WILLIAM B. GREENLEAF, OF NASHVILLE, TENNESSEE, ASSIGNOR TO CHARLES H. DE ZEVALLOS, OF NASHVILLE, TENNESSEE.

DETONATING DEVICE.

1,088,069.

Specification of Letters Patent.

Patented Feb. 24, 1914.

Application filed September 22, 1913. Serial No. 791,174.

To all whom it may concern:

Be it known that I, WILLIAM B. GREENLEAF, a citizen of the United States, residing at Nashville, in the county of Davidson 5 and State of Tennessee, have invented certain new and useful Improvements in Detonating Devices, of which the following is a specification, reference being had to the accompanying drawings.

10 This invention relates to certain improvements in detonating devices and has relation more particularly to a device of this general character in simulation of a fire arm and wherein a percussion cap is employed, and 15 the object of the invention is to provide a device of this general character having means of a novel and improved character whereby the explosion occurs within an inclosed chamber whereby the possibility of 20 injury due to the resultant sparks at the time of the explosion, is entirely eliminated.

The invention consists in the details of construction and in the combination and arrangement of the several parts whereby 25 certain important advantages are attained and the device is rendered simpler, less expensive and otherwise more convenient and advantageous for use, all as will be herein-after more fully set forth.

30 The novel features of the invention will be carefully defined in the appended claims.

In order that my invention may be the better understood, I will now proceed to describe the same with reference to the accompanying drawings, wherein—

Figure 1 is a view in side elevation of a detonating device constructed in accordance with my invention with the casing shown in open position and with the trigger in position to return to operative engagement with the hammer after a firing operation; Fig. 2 is a view similar to Fig. 1 with the trigger retracted to a point just before the release of the hammer and showing the feed for the 45 ammunition tape or band; Fig. 3 is a view in rear elevation of the device as disclosed in the preceding views with the casing in closed position; Fig. 4 is a view in front elevation with the casing in the same position 50 as in Fig. 3; Fig. 5 is a view in side elevation of the device as illustrated in Figs. 3 and 4; Fig. 6 is a view in perspective of the plate, herein employed for supporting the movable parts of my improved mechanism; 55 Fig. 7 is a view in perspective of the ham-

mer herein disclosed on an enlarged scale and detached; Fig. 8 is a view in top plan of the blank from which the hammer shown in Fig. 7 is produced; Fig. 9 is an enlarged fragmentary sectional view showing the 60 hinged connection between the sections of the casing, such sections being shown in their open position; Fig. 10 is an enlarged fragmentary sectional view showing the means for locking the sections of the casing 65 in closed relation; Fig. 11 is a view in rear elevation of the trigger as herein disclosed; Fig. 12 is a view in plan of the blank from which the trigger shown in Fig. 11 is produced; and Fig. 13 is a view in perspective 70 of the guide member herein employed.

My invention as herein embodied is shown as applied to a device in simulation of an automatic pistol but I do not wish to be understood as limiting myself to this particular form as it is thought to be obvious that my invention can be employed in connection with various forms of inclosing casings.

As herein disclosed, 1—1 denote casing 80 sections adapted to afford, when assembled, a chamber 2 substantially inclosed except at the forward end of the barrel portion 2 which end is provided with an opening 3 affording an exit for the exploded caps 85 which are produced on an elongated flexible strip or tape 4 in a manner well known, and in itself forms no part of the present invention. The opening 3, being the only point of discharge, also provides a means 90 through which the resultant sound of an explosion is directed and through which the smoke of the explosion also passes whereby it will be readily perceived that a close simulation is obtained by a pistol. The sections 1—1, as herein disclosed, are hingedly united along the free longitudinal edge portions of the barrel parts thereof and as herein set forth this hinged connection is afforded by providing one of the sections with the tongues 5—5 adapted to extend downwardly through suitable apertures 6—6 produced in the adjacent portion of the second section, such tongues 5 being annularly flexed in order that the sections 1—1 may 105 be readily and conveniently separated. In order, however, to hold such sections 1—1 normally in assembled position, the lower part of the butt portion of one of the sections is provided with a tongue 7 adapted 110

to overlap the adjacent similar portion of the second section 1 and such tongue 7 is provided with an indentation 9 adapted to be accommodated within a similar indentation 10 on the second section whereby it will be readily observed that the frictional contact of the tongue 7 will result in effectually maintaining the second sections in assembled position.

10 Insertible in the barrel portion of one of the sections 1 and suitably secured thereto by the rivets 11 and 12 is a plate 14 on which the firing mechanism is mounted and the upper marginal portion of such plate is provided with an inwardly directed flange 15 along which the tape 4 is adapted to travel in a manner to be hereinafter more particularly referred to. Also projecting inwardly of the plate is a pin 16 on which 20 is mounted for rocking movement the upwardly and forwardly directed hammer 17 having its upper or free end disposed on a bevel, as at 18, in order to properly contact, as at 19, with the flange 15, such portion of the flange 15 serving as the anvil. 25 The portion of the hammer 17 adjacent the pin 16 is enlarged and in the periphery of such enlarged portion at a point below and slightly in advance of the pin 16 is afforded 30 an open ended slot 20 into which the upper edge portion of the finger piece 21 of the trigger is adapted to project in order that such hammer may be adjusted into retracted position until the finger piece 21 is withdrawn from the slot 20, whereupon the hammer is forcibly brought into contact with the anvil 19 or more particularly the cap interposed therebetween through the medium 35 of the retractable spring 22 having one end portion suitably secured to the inwardly directed tongue 23 struck from the plate 14, while the opposite end of such spring is secured to the hammer 17 in advance of the pin 16; as herein shown in the drawings, 40 the engagement of the spring with the hammer is afforded by so producing the open ended slot 20 as to afford a shoulder 24 against which such spring bears. The body 25 of the trigger is provided with an elongated slot 26 through which a second pin 27, inwardly projecting from the plate 14, projects and serves as a fulcrum for the trigger, and the upper end portion of the body 25 of the trigger when pressure is applied upon the finger piece 21 is adapted 50 to contact with the tape and through coaction with the flange 15 to automatically feed the tape forward a distance sufficient to properly position a cap on the anvil 19 55 in order that the same may be exploded by the hammer 17 when the finger piece has been retracted a sufficient distance to become released from the slot 20, hereinbefore referred to. The finger piece 21 is normally 60 maintained within the slot 20 through the

medium of the retractable spring 28 secured at one end to the body 25 above the pin 27, while the opposite end thereof is anchored to an inwardly directed tongue 29 struck from the plate 14. In order to properly control the feed of the tape 4 to properly position the caps thereof relatively to the anvil 19, the upper end portion of such body 25 is caused to contact with an inwardly projecting lug 30 struck from the plate 14.

70 The tape or band 4 is inwardly rolled and is adapted to be mounted upon the inwardly directed portion of the rivet 12 and the free end portion thereof is then directed along the flange 15 and above the lug 30 which is elongated and serves to maintain such tape in operative position relatively to the hammer and anvil, as is believed to be obvious. It often occurs that the tape or band 4 during its travel or feed toward the anvil 19 becomes laterally displaced whereby certain of the caps are not properly engaged by the hammer 17 especially as the caps are not generally disposed in proper alignment on the tape as in the manufacture of these tapes or bands it often occurs that some of the caps are positioned beyond the transverse center of the tape or band to such an extent that but slight lateral displacement of the tape in its feed or travel will result in the non-explosion of these caps. As herein disclosed, the tape or band 4 is held against lateral displacement by the elongated guide flange 31 depending below the flange 15 and preferably positioned in proximity to the anvil 19, the distance between the guide flange 31 and the plate 14 being substantially equal to the transverse dimension of the band or tape 4. If desired this guide flange 31 may be formed integrally with the flange 15 but, as herein disclosed, it is produced with the angular plate 32 having its body portion interposed between the plate 14 and the adjacent wall of the section 1 with the angular portion 33 bridging the flange 15. 95 100 105 110 115 120 125 130

The hammer 17 may be formed as desired but it is preferred that the same be produced from a single piece of sheet metal as particularly indicated in Fig. 8, and wherein the contacting portion of such hammer is produced by suitably flexing the wings 34, as indicated in dotted lines in such figure, whereby the form of hammer particularly shown in Fig. 7 is produced. It is also preferred to produce the trigger 21 of sheet metal although I do not wish to be understood as limiting myself in this respect. As herein disclosed, this trigger is produced from a blank particularly illustrated in Fig. 12 wherein the body 25 of such trigger is initially of substantially oval form having a projected portion to afford the finger piece. The intermediate portion of the

blank adapted to form the body 25 is cut out, as at 35, in such a manner as to produce the inwardly directed finger 36 adapted to serve as an anchoring means whereby the 5 spring 28 may be secured to the body 25 as has been hereinbefore referred to. To either side of the cut out portion 35, the body 25 of the blank is provided with elongated openings which, when the device is properly folded in a manner which is thought to be obvious, afford the slot 26, hereinbefore referred to.

From the foregoing description of my improvements, it is thought to be obvious 15 that a detonating device constructed in accordance with my invention is of an extremely simple and comparatively inexpensive nature and is particularly well adapted for use by reason of the convenience and 20 facility with which it may be assembled and of the absolute protection afforded against injury from sparks at the time of the explosion and it will also be obvious from the foregoing description that my invention is 25 susceptible of some change and modification without material departure from the principles and scope thereof and for this reason I do not wish to be understood as limiting myself to the precise arrangement and formation of the several parts herein shown in 30 carrying out my invention in practice.

I claim:

1. A detonating device adapted to be employed in conjunction with an ammunition band and including a plate having a flange adapted to serve as an anvil, a hammer movably supported on the plate beneath the flange and adapted to contact with the anvil upon upward movement of the hammer, and 40 a guide plate having a marginal portion overlapping the plate and intersecting the plane in which the ammunition band travels and serving to hold such band against transverse movement.
- 45 2. A detonating device adapted to be employed in conjunction with an ammunition band and including a plate provided with a flange, a portion of such flange serving as an anvil, a hammer movable relatively to the anvil, a trigger mounted for rocking movement and for endwise movement, the rocking movement of the trigger serving to retract the hammer away from the anvil and the endwise movement of the trigger permitting 50 the same to coöperate with the

flange to impart feeding movement to the band relatively to the anvil when the trigger is rocked in one direction.

3. A detonating device adapted to be employed in conjunction with an ammunition 60 band and including a plate provided with a flange, a portion of such flange serving as an anvil, a hammer movable relatively to the anvil, a trigger mounted for rocking movement and for endwise movement, the rocking 65 movement of the trigger serving to retract the hammer away from the anvil and the endwise movement of the trigger permitting the same to coöperate with the flange to impart feeding movement to the band relatively to the anvil when the trigger is rocked in one direction, and a lug carried by the plate serving as a guide for the band and limiting the rocking movement of the trigger in one direction.

4. A detonating device adapted to be employed in conjunction with an ammunition band and including a plate having a flange, a portion of such flange serving as an anvil, a hammer movable relatively to the anvil, 80 and a guide plate overlapping the plate adjacent the anvil and having a marginal portion serving to hold the band against transverse movement.

5. A device of the character described 85 adapted to be employed in connection with an ammunition band and comprising a member serving to afford an elongated chamber having an opening through an end thereof and provided with a lateral extension intermediate the length thereof and serving as a hand grasp, detonating mechanism including an anvil and a hammer wholly inclosed within the member, the walls of the chamber adjacent the detonating mechanism being imperforate, and operating means for the hammer extending exteriorly of the member and positioned in close proximity to the hand grasp, such member also affording a chamber to receive the ammunition band, 90 the opening in the end of the member serving substantially as the only point of egress for the chamber and being positioned remote from the anvil.

In testimony whereof I hereunto affix my 105 signature in the presence of two witnesses.

WILLIAM B. GREENLEAF.
